CLEANING TOOL FOR SUCTION CLEANERS

Harry B. White, Canton, Ohio, assignor to The Hoover Company, North Canton, Ohio, a corporation of Ohio

Application June 10, 1948, Serial No. 32,142

6 Claims. (Cl. 15—339)

1

The present invention relates to suction cleaners and more particularly to a surface cleaning tool for use with suction cleaning apparatus.

An object of the invention is to provide a cleaning tool having large and small nozzles each of which is selectively operable for surface cleaning. Another object is to provide a cleaning tool having a pair of nozzles selectively operable by movement with respect to a surface engaging portion of the cleaning tool. Another object is to provide for free passage of a high velocity air stream over a nozzle mouth to remove dirt from the surface being cleaned. A further object is to provide a cleaning tool having valve means operative by movement of the surface cleaning nozzle with respect to the surface engaging portion of the cleaning tool. Other objects and advantages of the invention will be apparent from the following description and drawings, wherein,

Figure 1 is a perspective view of the cleaning tool attached to a suction cleaner;

Figure 2 is a perspective view of the cleaning tool with a portion broken away to illustrate the means for actuating the valve and to indicate the position of the valve;

Figure 3 is a sectional view showing the valve in position to connect the large nozzle with the source of suction; and

Figure 4 is a sectional view showing the valve in position to connect the smaller nozzle with the source of suction and also the high velocity air passageway.

The embodiment of the invention herein disclosed comprises a suction cleaning apparatus of the cylinder type having a casing 10 in which is disposed an unshown source of suction and a filter, and extending from the casing 10 is a flexible hose 11 attached to a rigid wand 12 connected to a cleaning tool 13.

The cleaning tool 13 includes a nozzle body provided with an elongated rectangular rear nozzle 15 having its mouth 16 defined at its surface contacting perimeter by a nozzle lip 17, and the mouth 16 communicates with an air passageway 18 which at its upper end connects with a passageway 19 disposed centrally in the upper portion of the body. Arranged at the outer end of the central air passageway 19 is a swivel joint 20 for connection to the wand 12.

Forwardly of the nozzle 15 is a front nozzle 22 having its mouth 23 defined by a perimeter lip 24, and the mouth 23 communicates with an air passageway 25 and an opening 26 to the central air passageway 19. The nozzle mouth 23 is disposed centrally of the cleaning tool and is of less extent

2

in cross section than the nozzle mouth 16 and is arranged at an angle with respect to the large nozzle mouth 16.

At the front of the nozzle body is a housing 30 having a top wall 31 and front wall 32, the latter provided with an opening 33 and a forwardly projecting wall 34. Disposed partially within the housing 30 is a partition 35 having a portion 36 spaced from the housing top wall 31, a front wall 37 and end walls 38—38. An arcuate portion 39 projects from the front wall 37 through the housing opening 33 and then inwardly of the housing projecting wall 34 and is provided with an opening 40 arranged above the small nozzle mouth 23. The lip 24 of the small nozzle opening 23 forms part of the partition 35 and the lip may be provided with a serrated edge to define the small nozzle mouth 23. A wall 42 is secured to the partition 35 and its lower end 43 is spaced upwardly from the front lip of the nozzle mouth 23. The partition 35, wall 42 and the projecting housing portion 34 cooperate to define a funnel 41 having a top inlet 44 and a lower outlet 45 adjacent to the small nozzle mouth 23 for passage of an air stream from above the nozzle mouth as shown by the arrows in Figure 4.

Disposed within the partition 35 is another wall 46 having a portion 47 resting against the front wall 48 of the air passageway 18. An opening 49 defined by a beveled edge 50 is spaced forwardly of the opening 26 in the air passage wall 48 for reception of a valve 51. The air passageway 25 is defined by the partition 35 and walls 42 and 46.

A surface engaging shoe 52 surrounds the exterior lips of the nozzle mouths 16 and 23 and comprises an irregularly shaped frame having a front wall 54, rear wall 55 and spaced end walls 56—56, the front and rear walls 54 and 55 having respectively surface engaging faces 57 and 58. The nozzle body is pivoted to the surface engaging shoe 53 by a pin 60 extending through each end wall 56 into the end wall 61 of the air passageway 18, whereby the nozzle may be moved with respect to the shoe 53 while the latter remains engaged with the surface being cleaned to selectively bring either of the nozzle mouths 16 or 23 into operative engagement with the surface being cleaned as shown in Figures 3 and 4.

The valve 51 includes a bottom wall 63, rear wall 64 and side walls 65—65 and is rigidly mounted on a rod 66 rotatably mounted in the end walls 38—38 of the partition 35. Rigidly connected to one end of the rod 66 is an arm 67 having its opposite end pivotally attached at 69 to a link 70 rotatably mounted at its lower end

by a pin 71 carried in a bracket 72 upstanding from the front wall 54 of the surface engaging shoe 53, whereby movement of the nozzle body with respect to the shoe 53 moves the valve 51 to its different positions shown in Figures 3 and 4. The periphery 73 of the valve side walls 65-65 are complementary to the beveled edge 50 of the opening 49 in the wall 46 and with the rear and bottom walls cooperate to close the opening 49 when the valve is in the position shown in Figure 3 in which position the small nozzle mouth 23 is cut off from and the large nozzle mouth 16 is connected to the source of suction. Movement of the valve 51 to the position shown in Figure 3 is limited by the periphery 73 of the valve side walls 65-65 abutting the beveled surface 50 of the opening 49 and by the top end 75 of the rear wall abutting a shoulder 16 on the wall 46. Movement of the valve to the position shown in Figure 4 is limited by the bottom wall 63 seating in a shoulder 77 formed in the rear wall of the air passageway 18.

In order to indicate when the valve 51 is in the position shown in Figure 4 to connect the small nozzle mouth 23 to the source of suction, the link 70 is extended upwardly as at 83 and provided with a laterally extending indicating element 84 which projects into the space 82 between the housing 30 and the partition 35. The housing 30 is provided with a slot 83 through which the indicating arm 84 can be observed when the small nozzle mouth 23 is connected to the source of suction. When the valve 51 is in the position shown in Figure 3 the small nozzle mouth 23 is disconnected from the source of suction and the indicating member 84 will be in the position shown in Figure 3 and thus not visible through the slot 83 to the operator.

In operation, when the cleaning tool is in use the air passageway 19 is connected to the wand 12 and flexible hose 11 to the source of suction in the casing 10. If it is desired to perform normal surface cleaning the large nozzle mouth 16 is moved with respect to the shoe 53 while the latter is in engagement with the surface being cleaned to the position indicated in Figure 3. In order to move the large nozzle mouth 16 from the inoperative position in Figure 4 to the surface cleaning position in Figure 3 the operator depresses the wand 12 to pivot the nozzle body clockwise on the pins 60 and relative to the shoe 53 while the latter is engaged with the surface being cleaned. Upon clockwise rotation of the nozzle body the valve 51 is moved counterclockwise by means of the bearing shoe 53, bracket 72, link 70, arm 67 and valve rod 66 to the position shown in Figure 3. In this position of the valve the small nozzle mouth 23 and air passageway 25 are disconnected from and the large nozzle mouth 16 connected to the source of suction. Also the large nozzle mouth 16 is supported by the shoe in operative position with respect to the surface being cleaned. The large nozzle mouth 16 provides for passage of a relatively large volume and low velocity air stream to remove nonimbedded dirt from the surface being cleaned. While the valve 51 is in the position shown in Figure 3 the indicator 84 cannot be seen through the slot 83 and thus the operator is informed that the valve 51 and large nozzle mouth 16 are in operative position.

If the dirt, threads or other litter cannot be removed by the large nozzle mouth 16 then the smaller nozzle mouth 23 is employed. The small nozzle mouth 23 is moved into operative position by lifting the wand 12 upwardly with respect to

the bearing shoe 53 while the latter remains engaged with the surface being cleaned. Lifting the wand 12 upwardly causes the nozzle body to pivot counterclockwise on the pins 60, and the flanges 90-90, only one of which is shown, on the housing 30 engage the front wall 54 of the shoe 53 to maintain the front wall 54 in contact with the surface being cleaned. Upon counterclockwise rotation of the nozzle body, the valve 51 is moved clockwise by the bearing shoe 53, bracket 72, link 70, arm 67 and valve rod 66 to the position shown in Figure 4 and such movement of the valve 51 is performed while the shoe 53 remains in contact with the surface being cleaned. While the valve 51 is being moved to the position shown in Figure 4 the indicator 84 is also shifted from the position shown in Figure 3 to that in Figure 4 whereby the operator can observe the indicator 84 through the slot 83 and thus be informed the small nozzle mouth 23 and valve 51 are in proper position. The indicator is moved by means of the valve shifting linkage and the extension 80 connected to the arm 84.

While the valve is being moved to the position indicated in Figure 4, the small nozzle mouth 23 is also shifted into operative relation with the surface being cleaned as shown in Figure 4 and is connected to the source of suction. In this position of the small nozzle mouth 23 the funnel 43 is connected with the atmosphere above the nozzle mouth and to the source of suction by the top inlet 44 and the lower outlet 45.

When the small nozzle mouth 23 is in this surface engaging position an air stream passes through the surface being cleaned and under the nozzle lip 24 into the air passageway 25 and 19 to the source of suction. The air stream passing through the small nozzle mouth 23 is of greater velocity than that which flows through the larger nozzle mouth 16 and thus functions to remove the litter clinging to the surface. An atmospheric air stream also enters the funnel 43 from the inlet 44 above the surface being cleaned and passes through the opening 40 and then the outlet 45 into the air passageway 25 to the source of suction. This atmospheric air stream as it passes beneath the lower end 43 of the barrier 42 through the constricted outlet 45 flows at high velocity and passes through the rug pile exposed in the nozzle mouth 23 to remove the clinging litter.

While I have shown and described but a single modification of my invention, it is to be understood that this modification is to be taken as illustrative only and not in a limiting sense. I do not wish to be limited to the particular structures shown and described, but to include all equivalent variations thereof except as limited by the scope of the claims.

I claim:

1. A surface cleaning tool comprising a body, means forming a first nozzle in said body, means forming a second nozzle in said body and having different operating characteristics than said first nozzle, means forming an air conduit for connecting said nozzles to a source of suction, valve means for selectively connecting said nozzles to the source of suction, a shoe engaging the surface being cleaned and having an opening into which said nozzles project, means movably mounting said body on said shoe in said opening to permit relative movement therebetween to selectively move either of said nozzles into engagement with the surface to be cleaned, and valve actuating means connected with said shoe

and valve means and responsive to said relative movement to move said valve means for selectively controlling communication of either of said nozzles with the source of suction.

2. A surface cleaning tool comprising a body, means forming a first surface engaging nozzle in said body, means forming a second surface engaging nozzle in said body and having different operating characteristics than said first nozzle, means forming an air conduit for connecting said nozzles to a source of suction, valve means movably mounted on said body for selectively connecting said nozzles to the source of suction, a shoe engaging the surface being cleaned, means rotatably mounting said body on said shoe to permit relative rotative movement therebetween to selectively move either of said nozzles into operative cleaning relation with the surface, valve actuating means connected with said shoe and valve means and responsive to said relative rotative movement to move said valve means for selectively controlling communication of either of said nozzles with the source of suction, and indicating means connected to said shoe and body and responsive to said relative rotative movement of said shoe and body to indicate when said valve means and one of said nozzles are in proper operating positions.

3. A surface cleaning tool comprising a body, means forming a nozzle mouth in said body engaging the surface to be cleaned, means for forming an air conduit for connecting said nozzle mouth to a source of suction for passage of a dirt-laden air stream through said nozzle mouth from the surface being cleaned, means defining an air passageway having an inlet for free passages of atmospheric air and an outlet connected to said air conduit, said air passageway directing an atmospheric air stream over the surface to be cleaned, a shoe engaging the surface to be cleaned, means movably mounting said body and thus said nozzle mouth on said shoe for relative movement therebetween, valve means for controlling the connection of said nozzle mouth and air passageway to the source of suction, and valve actuating means connected with said valve means and shoe and responsive to said relative movement of said body and shoe to move said valve means for controlling communication of said nozzle mouth and air passageway with the source of suction.

4. A surface cleaning tool comprising a body, means forming a first nozzle mouth in said body, means forming a second nozzle mouth in said body and having different operating characteristics than said first nozzle, means forming an air conduit for connecting said nozzle mouths to a source of suction for passage of dirt-laden air streams through said nozzle mouths from the surface being cleaned, means defining an air passageway connected to said air conduit through an outlet adjacent one of said nozzle mouths for directing an atmospheric air stream over the surface to be cleaned, valve means for selectively connecting said nozzle mouths and atmospheric air passageway to the source of suction, a shoe engaging the surface to be cleaned,

means movably supporting said body on said shoe for relative movement therebetween to selectively move either of said nozzle mouths into engagement with the surface being cleaned, and valve actuating means connected with said shoe and valve means and responsive to said relative movement of said body and shoe to move said valve means for controlling communication of said nozzle mouths and atmospheric air passageway with the source of suction.

5. A surface cleaning tool comprising a body, a nozzle in said body, an air conduit for connecting said nozzle to a source of suction, shoe means engaging the surface to be cleaned, means mounting said body on said shoe means for movement of said nozzle into and out of engagement with the surface, valve means movably mounted on said body for movement to one position to connect said nozzle with said air conduit when said nozzle is in said engagement with the surface, and movable to another position to disconnect said nozzle from said conduit when said nozzle is out of engagement with the surface, and valve actuating means connected to said valve means and shoe means and responsive to said movement of said body relative to said shoe means to move said valve to said one and said another positions and said nozzle into and out of engagement with the surface to be cleaned.

6. A surface cleaning tool comprising a body, means forming a first nozzle in said body, means forming a second nozzle in said body and having different operating characteristics than said first nozzle, means forming a conduit for connecting said nozzles to a source of suction, a shoe engaging the surface being cleaned, means movably mounting said body on said shoe for movement of said nozzles into selective engagement with the surface to be cleaned, valve means responsive to relative movement between said body and shoe for selectively connecting said nozzles to the source of suction, and valve position indicating means connected to said shoe and body and responsive to said relative movement of said shoe and body to indicate the position of said valve means in controlling communication of one of said nozzles with the source of suction.
